US00D971946S

(12) **United States Design Patent** (10) Patent No.: **US D971,946 S**
Chen et al. (45) Date of Patent: ** Dec. 6, 2022

(54) **DISPLAY SCREEN OR PORTION THEREOF
WITH GRAPHICAL USER INTERFACE**

(71) Applicant: **Apple Inc.**, Cupertino, CA (US)

(72) Inventors: **Kevin Will Chen**, Cupertino, CA (US); **Teofila Connor**, San Francisco, CA (US); **Alan C. Dye**, San Francisco, CA (US); **Aurelio Guzmán**, San Jose, CA (US); **Vincenzo Vuono**, Palermo (IT); **Christopher I. Wilson**, San Francisco, CA (US)

(73) Assignee: **Apple Inc.**, Cupertino, CA (US)

(**) Term: **15 Years**

(21) Appl. No.: **29/844,160**

(22) Filed: **Jun. 27, 2022**

Related U.S. Application Data

(63) Continuation of application No. 29/832,467, filed on Mar. 28, 2022, now Pat. No. Des. 956,079, which is a continuation of application No. 29/750,459, filed on Sep. 14, 2020, now Pat. No. Des. 949,169.
